TOY FIGURE

Joseph L. Kallus, Brooklyn, N. Y.

Application February 4, 1933. Serial No. 655,220

3 Claims. (Cl. 46—40)

My invention relates to toy figures such as dolls, toy animals and the like, and more particularly to toy figures in which the limbs and other members are jointed and movable relatively to each other. The object of the invention is to improve the construction of the limbs or other members of the toy figure with a view to increasing the efficiency thereof and to materially reduce the cost of production. The invention contemplates further the provision of an improved and novel means for maintaining the several parts of the toy figure in the desired assembled condition and to increase the efficiency of the connecting means at a reduction in the cost of manufacture and assembling the parts. Other objects will appear from the description hereinafter and the features of novelty will be pointed out in the claims.

In the accompanying drawing, which illustrates examples of the invention without defining its limits, Fig. 1 is an elevation, partly in section, of a doll embodying the novel features; Fig. 2 is an enlarged sectional view of a leg member constructed in accordance with the invention; Fig. 3 is a detail section on the line 3—3 of Fig. 1; Fig. 4 is a fragmentary elevation of said leg member showing the construction thereof; Fig. 5 is a fragmentary view of said leg member in an assembled condition looking at right angles to Fig. 4; and Fig. 6 is an enlarged fragmentary section illustrating a novel detail of the fastening means whereby the parts of the toy figure are connected in an assembled condition.

For convenience of illustration and description I have shown the novel arrangements embodied in a doll for which the invention is particularly adapted; it is to be distinctly understood however that this is only an example and that the novel features may be embodied with corresponding advantages in toy figures of other types.

In the illustrated example the jointed doll comprises a body 10 shown of hollow form and constructed of any suitable material, which is either inherently rigid or, if flexible or yielding, is made rigid at predetermined points or in its entirety in any conventional manner as may be necessary to effect a natural or other predetermined appearance. A customary head 11 is mounted on the body 10 or on a neck member thereof in any well known way, and said body 10 is further provided with arm sockets adapted to receive the arm members 12, the latter being constructed, for instance as shown in Fig. 1, of a plurality of relatively movable sections fitted

together in any manner to provide the desired articulation or other arrangement. The detailed construction of the body 10 and head 11 is of no consequence as such detailed arrangement is no part of the invention; the same is true of the arm members 12 excepting as qualified and pointed out in the description hereinafter. If the body 10 is made of resilient or equivalent non-rigid material and is to include the property of being yielding to more closely approximate the natural body which it is intended to simulate, or to provide other predetermined characteristics in the toy figure, suitable provision may be made to provide rigidity at such points where it is required.

In toy figures of the kind under discussion, the bodies, at predetermined portions thereof, are shaped and constructed in a manner to provide for the desired adjustments and movements of the various sections, and more particularly the limb members thereof, in a manner corresponding to the natural movements of the parts which such sections and members are intended to simulate. Thus the body 10 of the doll, in the illustrated example, is tapered at its lower portion to provide a pelvis portion having downwardly and inwardly converging external surfaces 13 in which the leg sockets 14 or their equivalent are formed; in the event that the body 10 is hollow, as in the illustrated example, these sockets 14 may extend completely through the walls of said body as shown. This arrangement and construction of the body 10 is not in itself new and per se constitutes no part of the instant invention.

The toy figure, or specifically the doll of the example shown in the drawing, further comprises leg members which, in all forms, are provided with sections 15, referred to for convenience of description, as upper sections in order to positively identify the same. In the doll, as illustrated, the leg members further consist of knee sections 16, lower leg sections 17, and feet sections 18 fitted together to provide an articulated construction. It is to be understood that the detail construction of the leg members or their equivalent may be different from that shown in the drawing, such construction being dependent upon the type of the doll or other toy figure for which they are designed; in all forms the leg members or their equivalent include portions which correspond to and are intended to be covered by the designation, upper sections. To permit the doll to assume a sitting position, and to enable the leg members or their equivalent to be adjusted to make possible other postures

in the doll or other toy figures, the upper sections 15 are provided at their upper or equivalent ends with hemispherical projections 19 adapted to be seated in the sockets 14, which projections 19 may be truncated as shown although this is optional and not necessary; in addition the sections 15 in order to provide the desired range of adjustment in a life-like manner are required to include relatively inclined surfaces 15^a corresponding more or less, in inclination at least, to the surfaces 13. The upper sections 15 and the sections 19 thereof may further include such other features as are commonly found in the corresponding parts of toy figures, or may be provided with special features incidental to the toy figures for which said sections and projections are designed. The projections 19 and the sockets 14 of the illustrated doll correspond to the hip joints of a human being and function in a manner to simulate the action of such hip joints. It will be obvious that the projections 19 and the sockets 14 in which they are seated may correspond in location and function to other joints of the human body or to parts of the body of such other natural animal intended to be simulated.

In order to obtain the desired results, the upper leg sections 15 and their equivalents, have heretofore generally been produced by molding, and accordingly have been made of a suitable composition or an equivalent material capable of being molded, which becomes hard in its final form. The production of such sections by molding is expensive and results in the formation of external seams which unless the evidence thereof is removed affect the appearance of the sections; in addition the character of the composition or other moldable material is such that considerable loss results from breakage and other damage in the production of the sections in question. To overcome these objections and to produce the sections in an efficient and economical manner, the sections 15, in the instant case, are made of wood, or other material capable of being turned, and consist of two elements 15^b and 15^c independently made and then connected with each other. The main or thigh element 15^b is preferably made by turning the wood or its equivalent to proper form and providing said element 16^b with the relatively inclined surface 15^a. The auxiliary or joint element 15^c is made by turning a wood unit or its equivalent, for instance, to the form of a complete sphere, which is then cut in half to provide hemispherical elements 15^c each of which is fastened in surface engagement with the inclined surface 15^a of a given section 15 with the major axis of the joint element 15^c perpendicular to said inclined surface 15^a; any suitable and convenient means may be used for fastening the elements 15^c in place, the illustrated example showing nails 15^d as the fastening devices whereby the elements 15^c are secured to the elements 15^b. The turning operation of the wood or its equivalent is so carried out that the hemispherical elements 15^c will have plane surfaces, the diameters of which correspond to the transverse width of the inclined surfaces 15^a. When fixed in place each element 15^c is located in coterminous registry with one end portion of the associated inclined surface 15^a thus leaving the remainder of said surface free and exposed as shown in Figs. 2 and 5; if necessary the sections 15 may be finished in any customary manner subsequent to the attachment of the elements 15^c to provide smooth and even surfaces. In any

case the finished product comprises an efficient upper leg section 15 or its equivalent produced with a minimum of labor and at a minimum cost with practically no loss from breakage or other causes.

In dolls and other toy figures of the jointed type under discussion the various parts comprising the figure are movably held together in assembled relation generally by means of elastic cords 20 properly located to effect the desired result. Heretofore the anchorages for such elastic cords have presented difficulties which have increased the cost of production of the toy figures and added to the time required therein. In the instant case these difficulties and objections have been overcome by providing the elastic cords 20 or their equivalents with tubular metallic sleeves or gromets 21 into and preferably through which the free ends of said cords 20 or the like extend as shown in Figs. 2 and 6; the sleeves or gromets 21 may be fastened in place on said cords 20 or their equivalent in any convenient manner as by suitably punching said sleeves or gromets 21 to provide inwardly extending projections or lugs 22 which clamp and secure the cords or the like 20 against withdrawal from said sleeves or gromets 21 as illustrated in Fig. 6. In the form shown in the drawing the sleeves or gromets 21 are provided at one end with circular flanges 23 of a diameter greater than the external diameter 100 of the gromets 21.

The utility and operation of this novel arrangement is shown in the illustrated example in connection with the leg members of the doll shown in the drawing; it will be understood that it will function and operate in a similar manner in connection with other parts of the doll, as for instance the arm members 12 thereof, or in connection with the elements comprising the parts of other types of toy figures.

In the assembled condition of the doll shown in the drawing the flanges 23 of the gromets or sleeves 21 are located in recesses 24 formed in the bottoms of the feet sections 18 so as to engage the bottoms of said recesses 24 as shown in Fig. 120 2; the tubular sleeves or gromets 21 projecting from said flanges 23 are fitted in and extend through openings 25 formed in said feet sections 18 and communicating with openings 26 with which said sections are provided. From the 125 sleeves or gromets 21 the cords 20 extend through registering bores 26 formed in the respective sections of the leg members of the doll as illustrated in Fig. 2. In the doll of the drawing the sleeves or gromets 21 are secured to the opposite ends of a continuous elastic cord or the like 20 and are located in the feet sections 18 with the flanges 23 located in the respective recesses 24 thereof; the cord or the like 20 passes upwardly through the leg members and body of the doll and over a 135 conventional fastening device, such as a hook, provided in the customary manner interiorly of the head 11. The arrangement and proportion of the parts is such that, in the assembled condition of the doll, the cord 20 or its equivalent is under tension and thus develops a pulling force between the flanges 23 of the sleeves or gromets 21, in combination with the bottoms of the recesses 24, and the aforesaid fastening device interiorly of the head 11, whereby the leg members 15, 16, 140 17 and 18, the body 10 and the head 11 are movably held together in an assembled condition with a maximum of efficiency and in a simple manner. The novel means described above with respect to the illustrated doll, obviously will operate in the 145 150

same manner and with equal efficiency for holding other parts of the doll, and the component parts of other toy figures, together in an assembled condition, and in all cases will permit life-like or other predetermined movements and adjustments of the various parts without interference. The novel means for anchoring the elastic cords 20 or their equivalent also permits repairs and replacements to be made in the toy figures with a minimum of effort and at a minimum of expense, and entirely avoids the necessity for using nails or the like and other more or less complicated devices for effecting the desired anchorages; at the same time the novel anchorages do not affect the appearance of the toy figure as such anchorages are substantially invisible in all normal positions of the toy figure and even when visible do not objectionably intrude themselves upon the eye of the observer.

With the novel arrangements set forth herein it is possible to cheaply and efficiently produce the upper leg sections or equivalent parts of jointed dolls and other articulated toy figures from wood or equivalent material by turning, and to avoid the complication, loss by breakage and the like, and other disadvantages of the conventional molded processes heretofore deemed necessary in the production of such elements. At the same time the operation of anchoring the elastic cords or the like whereby the parts of the toy figures are held together in an assembled condition is greatly simplified and perfected at a relative reduction in cost, time of production and degree of skill required in the manufacture of such toy figures.

Various changes in the specific forms shown

and described may be made within the scope of the claims without departing from the spirit of the invention.

I claim:

1. In an articulated toy figure including a body provided with sockets and limb members in jointed connection with said body, that improvement which comprises an upper limb section consisting of a main element of turned wood having an inclined end surface, and an independent hemispherical joint element of turned wood having its flat surface secured in surface engagement with said inclined surface, said joint element being adapted to fit a socket of said body. 80
2. In a jointed doll including a body provided with leg sockets and leg members in jointed connection with said body, that improvement which comprises an upper leg section consisting of a thigh element of turned wood having an inclined end surface, and an independent hemispherical joint element of turned wood having a plane surface corresponding to the width of said inclined surface, said plane surface being fastened in surface engagement with said inclined surface in coterminous registry with a portion thereof, and 85 said joint member being adapted to fit a leg socket of said body. 90
3. A leg member for dolls comprising a thigh element of turned wood having an inclined end surface, and an independent hemispherical joint element of turned wood having its plane surface secured in surface engagement with said inclined surface in coterminous registry with an end portion thereof. 95 100 105
